UNITED STATES PATENT OFFICE.

RICHARD VARLEY, OF ENGLEWOOD, NEW JERSEY.

IGNITION APPARATUS AND SYSTEM AND METHOD OF SPARK CONTROL.

1,149,798.

Specification of Letters Patent. Patented Aug. 10, 1915.

Application filed December 23, 1913. Serial No. 808,378.

To all whom it may concern:

Be it known that I, RICHARD VARLEY, a citizen of the United States of America, residing at Englewood, in the county of Bergen and State of New Jersey, have invented new and useful Improvements in Ignition Apparatus and Systems and Methods of Spark Control, of which the following is a full, clear, and exact description, reference 10 being had to the accompanying drawings, which form part of this specification.

This invention relates to ignition apparatus for use with internal combustion engines and more particularly to the generator 15 or magneto electric machine and its associated mechanism.

Generally, I provide new and improved means for adjusting the timer or interrupter and distributor devices with respect to the 20 engine, and also means for adjustably maintaining the wave peak of the current from the armature of the generator in synchronous relationship with the interrupter and distributor.

25 It is well understood that upon inauguration of the spark, burning or explosion of the gaseous charge in the cylinders of the engine does not immediately take place, the moment of ignition being dependent upon 30 the character of the gas charge and degree or intensity of compression thereof; the desirable moment, however, usually being at the point of greatest compression. Where, with given throttle conditions, it is desired 35 to operate the engine at a certain speed, it is usual for the operator regarding the behavior of the engine, to so manipulate the spark control as to find the most advantageous point or moment of ignition. Thus 40 as the engine speed builds up the sparks must be produced more and more in advance of their previous position relative to the piston position so as to preserve this period of ignition; over-advance of the 45 spark producing a characteristic pounding or "knocking" in the engine and lateness in the spark resulting in inefficiency or loss of power in operation and also in heating of the cylinders.

50 It is well understood that the current wave to some extent lags behind the impressed electromotive force or the peak of the current wave occurs later in the revolution of the armature of the magneto or gen-

erator when the speed of rotation is high 55 than when it is low; this armature lag being due, as is known, to different causes, such as inductance and armature reactance, and it is also well known that when the interrupter mechanism is advanced as the speed of the 60 engine increases, responsive acceleration in travel of the armature causes the peripheral velocity thereof to shift the lines of magnetic flux in the direction of armature rotation, with the result that the current wave 65 peak assumes an added delay phase with respect to the interrupter mechanism on account of the retardation of the voltage wave peak.

Inasmuch that in order to produce an 70 effective spark the interrupter contacts should operate to form the spark at a suitable point in the current wave, it follows that to permit of adjustment of the moment of ignition, for all speeds of the engine, the 75 current phases of the generator must be correspondingly controlled. This has long been sought to be accomplished by mounting the armature in a rotatively adjustable manner for the purpose of advancing it, so that upon 80 increase in speed of the armature, attending shifting of the alternating current wave brings the current wave peak into substantial synchronism with the interrupter. However, in such construction, the interrupter 85 and distributor mechanism is so associated with the armature of the generator that the range of angular adjustable movement of the armature can not exceed or vary from that of the interrupter and distributor, so 90 that it is impossible to shift the armature with a view to synchronizing the current wave peak and interrupter after the latter has been adjusted to full advance position; the current wave shifting to an ineffective 95 position in a direction opposite to that of advance movement of the interrupter mechanism.

By my invention, upon adjustment of the 100 interrupter mechanism to effect explosion of the charge at the proper or most favorable time, whether the engine is running at reduced or advanced speed, the current wave peak is thereby always brought into substantial coincidence with the time of operation of the interrupter and distributor, resulting in desired synchronizing of the current wave peak and interrupter and dis-

- tributer with the desired period of inauguration of the spark, regardless of the degree of shifting of the armature necessary to obtain such coincidence. For instance, where 5 the interrupter mechanism is advanced with the usual, but not always, attending increase in armature speed responsive to which would be an increase of voltage, a forward shifting of the voltage peak and an increase of the 10 angle of the lag of the current behind the voltage, the latter resulting from increase of current strength, to a degree greater than the possible angular advance movement of the interrupter, nevertheless, the current 15 wave peak is brought or restored to normal, or is substantially coincidental with that of operation of the interrupter adjusted to produce the spark at a period of time properly related to the moment of ignition.
- 20 I will now describe my invention so that others skilled in the art to which it appertains may understand and construct the same, it being premised, however, that changes may be made in the construction 25 shown and described, within the scope of the appended claims.

Figure 1 is a side elevational view of ignition apparatus involving my invention; Fig. 2 is a top plan view of the same, partly 30 broken away; Fig. 3 is an enlarged transverse sectional-elevational view taken on the line 3—3 of Fig. 1; Fig. 4 is an enlarged fragmentary view of the apparatus but showing the interrupter cam and associated 35 contact mechanism removed; Fig. 5 is a longitudinal sectional view showing means for adjusting the armature of the generator and interrupter and distributer mechanism; Fig. 6 is a diagrammatic view illustrating the 40 principle of my invention; and Fig. 7 is a similar view showing modified manner of adjusting the interrupter and distributer elements.

In connection with the ignition system 45 shown in Figs. 6 and 7, I have shown an improved form of transformer which forms subject matter of Letters Patent 1081413, issued to me on December 16, 1913 and a detailed description of which, in this specification, is not necessary to an explanation of the present invention.

The generator may be of any suitable general construction, *i. e.*, having a permanent or an excitable field, as desired, and either 55 an ordinary H-armature or one that is drum wound and provided with slip rings and collector brushes for the purpose of taking off alternating current; employment of a drum wound armature, as incident to its use in 60 a combined lighting and ignition generator in automobile equipment producing an advantageous wave form of voltage. My invention therefore, may be used to great advantage with machines having drum wound armatures, although it will be understood 65

that I do not limit myself to such use; it being apparent that I may embody the invention in or apply it to the regular ignition magneto having an H-armature.

Referring to Figs. 1, 2, 3 and 4, the reference numeral 2 indicates an electric generator adapted to energize an ignition circuit, such as indicated in Fig. 6, in which view the armature 3 of the generator is shown. The armature has a shaft 4, as 70 shown in Figs. 4 and 5, that is spirally milled or cut away as at 5. Driving of the shaft 4 for rotation of the armature is effected from a shaft 6 by means of a coupling sleeve 7; power to the shaft 6 being transmitted from the engine in a well known manner. The spirally milled portion of the armature shaft fits into a complementary broached or spiral bore in one end of the sleeve which latter is longitudinally shiftable 75 along and rotates with the shaft 6, as by being fitted to the square-finished end 8 of the shaft. The length of the sleeve 7 is such as to permit of shifting thereof on the square end of the shaft 6 the full length 80 of the spiraled portion of the armature shaft, which shifting may be effected, as shown in Figs. 1 and 2, by means of a yoke 9 carried by a slide bar 10 mounted along 85 one side of the generator frame and provided with an operating lever 11. As shown in Fig. 5 the armature shaft may have a reduced stub portion 4^a fitting in a bore in the shaft 6, for the purpose of preserving alignment of the shafts and thereby preventing 90 any tendency to deflection of the armature shaft and binding of the sleeve 7 against free movement along the shaft 6.

Formed on or carried by the sleeve 7 is a spiral gear 12 meshing with which is a 105 spiral gear 13 mounted to operate the usual interrupter or timer and distributer mechanism, the former mechanism comprising, as clearly shown in Fig. 3, essentially a fixed contact member 14, a movable contact lever 110 15 and an actuating cam 16, that, being fixed to the shaft 17 of the gear 13, is adapted to be driven in synchronism with the engine. The distributer apparatus 18 is arranged to be operated in unison with the interrupter mechanism, as through beveled gears 19 and 20; the gear 19 being carried by the gear 13 or its shaft and the gear 20, as shown in Fig. 6, directly driving the revoluble distributer arm 21. As shown in Figs. 1, 2 115 and 4, the gear 12 is of such width that the sleeve 7 may be shifted backward and forward without bringing the said gear out of mesh with the gear 13.

The direction of the spiral of the milled portion 5 of the armature shaft (see Figs. 4 and 5) is made such that when the sleeve 7 is shifted toward the armature the shaft 4 thereof will be rotated relatively to the shaft 6, in the normal or same direction of 120 125 130

rotation and also the direction of the spiral of the teeth of the gears 12 and 13 is such that when the sleeve 7 is advanced toward the armature the teeth of the gear 12 set up 5 cam action on the meshing teeth of the gear 13 with the result that the latter gear is rotated relatively to the shaft 6 and in such direction as to advance the actuating cam of the interrupter mechanism, as clearly 10 shown in Fig. 3. Of course, the return movement of the sleeve sets up a reverse action on the shaft 4 (see Fig. 4) and the gear 13; the armature and interrupted cam being thereby rotatively retarded relatively 15 to the movement of the shaft 6.

It thus will be seen that upon forward shifting of the sleeve 7 toward the armature, the interrupter mechanism will be accordingly advanced, likewise the armature 20 of the generator is advanced so that the current wave will be pre-formed in such manner as to bring its peak slightly but not ineffectively away from the point of opening of the interrupter. With increase in or 25 acceleration of the speed of the engine, the generator armature is driven at increased speed, causing thereby such shifting of the current wave peak from the generator as results in movement of the current wave peak 30 to normal, *i. e.*, restoration to a position substantially coincident with the period of operation of the interrupter. Upon further advance of the sleeve 7 the above conditions are repeated; the range of movement of the 35 interrupter mechanism being that of the usual apparatus.

The lead of the spiral of the armature shaft and the gear teeth may vary according to conditions. Thus where the desired angular degree of shifting of the armature would not in any case exceed that of the interrupter cam in its adjustment for spark control, the leads may be such as to maintain substantial uniformity of travel between 40 these two elements, or they may be such that the current wave peak takes a predetermined point when the interrupter contacts separate at slow speed of the engine and a different point when they separate at an advanced speed. When the desired angular 45 degree of adjustment of the armature would exceed that of the normal adjustable movement of the interrupter mechanism, the spiral lead of the armature shaft would be more acute than that of the gears. If in 50 the control of the spark at various speeds the angular cumulative movement of adjustability of the armature were to reach 80 degrees and the normal adjustable travel of 55 the interrupter mechanism were 10 degrees, the lead of the spiral of the armature shaft would bear such proportion to that of the gears as to cause proportional travel within 60 the 10 degrees of the interrupter mechanism 65 to the 80 degrees of travel of the armature.

As a result when the sleeve 7 is shifted to regulate the spark with respect to the engine, the armature of the generator is always concomitantly proportionately adjustably rotated so that the current wave peak 70 is kept substantially coincident with the operation of the interrupter mechanism.

In Fig. 7 I show a modified form of connection between the armature and the interrupter mechanism. The armature shaft is 75 shown as having fixed to it a plain gear 12' meshing with which is a gear 13' that is arranged to operate the interrupter cam 16 and also drive the distributor arm 21 through the beveled gears 19' and 20'. The 80 ratio between the gears 12' and 13' is such as to cause normal commensurate operation of the interrupter and distributor devices. The timber contacts are mounted for 85 rotative adjustment about the cam 16.

It will be seen that when the armature is 90 adjustably shifted by the sleeve member 7, the gear 12' will in turn shift the gear 13' and interrupter mechanism relatively to the shaft 6; the degree of angular travel of the 95 interrupter being, as will be understood, less than that of the armature by reason of the fact that the gear ratio is such as to cause synchronous operation of the cam with each rise of the current wave to maximum. If the range of angular adjustable movement imparted to the cam by the armature, through the gears 12' and 13', exceeds that of the normal possible range of adjustment 100 of the interrupter, the casing or support 16^a carrying the interrupter contact mechanism, (as well as the distributor casing 18^a) upon shifting of the armature, may be so shifted relatively to and in the direction of rotation of the cam as to obtain substantial proportional movement between the interrupter mechanism, distributor and armature. This 105 proportional adjustment may be automatically effected, as will be apparent without necessity of specific illustration, by connecting the casings 16^a and 18^a to the usual spark adjusting levers or mechanism for shifting the sleeve 7. Or instead of such proportional movement, the contact mechanism need not be shifted relatively to the 110 interrupter cam until full advance position of the cam has been reached, in which case, upon further movement of the armature, the said contacts may be shifted in unison with the cam, thereby preserving the point 115 of inauguration of the spark but permitting the armature to be advanced to correct the effect of current wave shifting.

The advantages of my invention will be 120 appreciated by those skilled in the art. In 125 prior forms of ignition apparatus, it has been impossible to properly synchronize the interrupter mechanism with the current phases, the flux distortion, upon increase in speed, also the current lag, causing the wave 130

to shift to a degree impotent to effective ignition.

While I have described my invention as associated with apparatus in which the time of the voltage peak of the generator relative to the interrupter is varied by shifting of the armature, I do not desire to limit myself thereto as such movable element instead of constituting the armature, may be that of a movable field or equivalent member, such as adjustable pole pieces between the field and armature for the purpose of shifting the magnetic poles. Furthermore, while I have shown a particular form of shifting apparatus, and gear arrangement, it is obvious that they may also be varied, and that other changes may be made, all of which, it being understood, coming within the scope of the appended claims.

Having thus described my invention, what I claim and desire to secure by Letters Patent is:

1. In ignition apparatus for internal combustion engines, an electric generator having a positively driven revolute member capable of adjustment for regulating the generator phases, shiftably adjustable ignition controlling mechanism, means for shifting the said member within a range greater than the possible range of adjustment of the controlling mechanism, and means for adjustably shifting the controlling mechanism.

2. In ignition apparatus for internal combustion engines, an electric generator having a positively driven revolute member capable of adjustment for regulating the generator phases, shiftably adjustable ignition controlling mechanism, means for adjustably shifting the said member at one rate or progression relatively to the engine, and means for shifting the controlling mechanism at a different progressive rate.

3. In ignition apparatus for internal combustion engines, an electric generator having a revolute armature, shiftably adjustable ignition controlling mechanism, means for rotatively adjusting the armature for regulating the current phases thereof, at a predetermined rate of progression, and means for shifting the controlling mechanism at a different rate.

4. In ignition apparatus for internal combustion engines, an electric generator having a revolute armature, shiftably adjustable ignition controlling mechanism, means for rotatively adjusting the armature for regulating the current phases thereof and to an angular degree greater than the degree of adjustable movement of the controlling mechanism, and means for so adjusting the controlling mechanism as to maintain substantial synchronism between the controlling mechanism and the current phases.

5. In ignition apparatus for internal combustion engines, an electric generator having

a revolute armature, shiftably adjustable ignition controlling mechanism, means for rotatively adjusting the armature for regulating the current phases thereof, at a predetermined rate of progression, and common means for actuating the controlling mechanism and for adjusting said mechanism at a proportional differential rate of travel.

6. In ignition apparatus for internal combustion engines, an electric generator having a revolute armature, a shaft for transmitting power from the engine to the armature, ignition controlling mechanism adapted to be driven by said shaft and capable of spark adjustment, means associated with said shaft for rotatively shifting the armature relatively to the movement of the shaft, for regulating the current phases thereof, and means for shiftably adjusting the controlling mechanism at a rate of progress different from that of the rotative regulative movement of the armature.

7. In ignition apparatus for internal combustion engines, an electric generator having a revolute armature, a shaft for transmitting power from the engine to the armature, ignition controlling mechanism adapted to be driven by said shaft and capable of spark adjustment, means associated with said shaft for rotatively shifting the armature relatively to the movement of the shaft, for regulating the current phases thereof, and means for shiftably adjusting the controlling mechanism at a proportional rate of progress different from that of the rotative regulative movement of the armature.

8. In ignition apparatus for internal combustion engines, an electric generator having a revolute armature, a shaft for transmitting power from the engine to the armature, ignition controlling mechanism capable of spark adjustment, connections between the shaft and controlling mechanism for operation of the latter, means associated with said shaft for rotatively shifting the armature relatively to the movement of the shaft, for controlling the current phases thereof, and means, comprising said connections between the power shaft and controlling mechanism, for adjusting the latter mechanism.

9. In ignition apparatus for internal combustion engines, an electric generator having a revolute armature, a shaft for transmitting power from the engine to the armature, ignition controlling mechanism capable of spark adjustment, gearing whereby the said shaft may operate the controlling mechanism, means associated with said shaft for rotatively shifting the armature relatively to the movement of the shaft, for controlling the current phases thereof, and means comprising said gearing, for adjusting the controlling mechanism.

10. In ignition apparatus for internal

- combustion engines, an electric generator having a member capable of adjustment for regulating the generator phases, shiftably adjustable ignition controlling and distributor mechanism, means for adjustably shifting the said member at one rate of progression, and means for shifting the controlling and distributor mechanism at a different rate of movement.
11. In ignition apparatus for internal combustion engines, an electric generator having a revoluble armature, shiftably adjustable ignition controlling and distributor mechanism, means for rotatively adjusting the armature for regulating the current phases thereof, at a predetermined rate of progression, and means for shifting the controlling and distributor mechanism at a differential rate of movement.
12. In ignition apparatus for internal combustion engines, an electric generator having a revoluble armature, ignition controlling and distributor mechanism adapted to be driven by said shaft and capable of spark adjustment, means associated with said shaft for rotatively shifting the armature relatively to the movement of the shaft, for controlling the current phases thereof, and means for shiftably adjusting the controlling and distributor mechanism at a proportional rate of progress different from that of the rotative adjustable movement of the armature.
13. In ignition apparatus for internal combustion engines, an electric generator having a revoluble armature, a shaft for transmitting power from the engine to the armature, ignition controlling and distributor mechanism capable of spark adjustment, gearing whereby the said shaft may operate the controlling and distributor mechanism, means associated with said shaft for rotatively shifting the armature relatively to the movement of the shaft, and means, comprising said gearing, for adjusting the controlling mechanism.
14. In ignition apparatus for internal combustion engines, an electric generator having a member capable of adjustment for regulating the generator phases, means for adjustably shifting the said member, shiftable ignition controlling and distributor mechanism including a contact actuating device movable upon adjustment of the said generator member, and means for also effecting shifting of the controlling and distributor mechanism.
15. In ignition apparatus for internal combustion engines, a shaft driven by the engine, an ignition generator, a variable connection between the shaft and generator, ignition controlling mechanism, and a variable connection between the shaft and the controlling mechanism.
16. In ignition apparatus for internal combustion engines, a shaft driven by the engine, an ignition generator, a controllable generator phase varying and driving connection between the shaft and generator, ignition controlling mechanism, and a variable connection between the shaft and the controlling mechanism.
17. In ignition apparatus for internal combustion engines, a shaft driven by the engine, an ignition generator, a controllable generator phase varying and driving connection between the shaft and generator, ignition controlling mechanism, and a variable connection between the shaft and the ignition controlling mechanism and associated with the said driving connection.
18. In ignition apparatus for internal combustion engines, a shaft driven by the engine, an ignition generator, a variable driving connection between the shaft and generator, ignition controlling and distributor mechanism, and a variable actuating connection between the shaft and the said mechanism and operatively associated with the variable driving connection.
19. In ignition apparatus for internal combustion engines, a generator having an armature, a shaft therefor, having a spiral cam surface, a driving connection between the engine and the shaft and adapted to co-operate with the spiral cam surface for effecting rotative adjustment of the armature, ignition controlling mechanism, and a longitudinally shiftable gear associated with the shaft and adapted to actuate the controlling mechanism.
20. In ignition apparatus for internal combustion engines, a generator having an armature, a shaft therefor having a spiraled surface, a shiftable driving connection between the engine and the shaft and adapted to co-operate with the spiraled surface for effecting rotative adjustment of the armature, ignition controlling mechanism, and a gear carried by said driving connection and associated with the shaft and adapted to actuate and effect spark adjustment of the controlling mechanism.
21. In ignition apparatus for internal combustion engines, a generator having an armature, a shaft therefor having a spiral cam surface, a shiftable driving connection between the engine and the shaft and adapted to co-operate with the spiral cam surface for effecting rotative adjustment of the armature, ignition controlling and distributor mechanism, and a gear carried by said driving connection and associated with the shaft and distributor mechanism.
22. In ignition apparatus for internal combustion engines, a generator having an armature, a shaft therefor having a plurality of flat faces helically directed, and a sleeve member having a helical bore adapt-

ed to receive the helical portion of the shaft and shiftable over the spiral portion of the shaft to effect rotative adjustment of the armature.

5 23. In ignition apparatus for internal combustion engines, a generator having an armature, a shaft therefor, provided with a helical portion substantially square in cross-section, and means associated with said helical portion for effecting rotative adjustment of the armature.

10 24. In ignition apparatus for internal combustion engines, a generator having an

armature, a shaft therefor having a substantially square helically directed portion, 15 and a shiftable sleeve member associated with said helical portion for effecting rotative adjustment of the armature.

In testimony whereof, I have hereunto set my hand in the presence of two witnesses. 20

RICHARD VARLEY.
